HOSPITAL BED WITH BEDPAN ADMINISTRATION MEANS

Filed May 9, 1927

INVENTOR.
C. H. Horst

BY Fred A. Taylor

ATTORNEY.

UNITED STATES PATENT OFFICE.

CHRISTIAN H. HORST, OF LOS ANGELES, CALIFORNIA.

HOSPITAL BED WITH BEDPAN ADMINISTRATION MEANS.

Application filed May 9, 1927. Serial No. 189,911.

My invention relates to hospital or invalid beds, and more particularly to a means whereby the administration of a bed pan to the patient may be facilitated.

5 It accordingly is an object of my invention to provide a novel form of apparatus in which a hospital or other bed has its wire mattress equipped with a framework defining an opening therein which opening is adapted to be opened and closed by means of a trap connection, of a framework hinged to the framework of said mattress, means being provided for locking said trap in position when the bed pan is not in use, the bed pan 10 used with said mattress being provided with an opening, into which may be fitted a block, preferably in the form of a truncated pyramid equipped with suitable fasteners whereby said block may be detachably positioned 15 in said opening, said block being also provided with tabs or strings or other means whereby said block may be detachably associated with said trap to close or open the opening in said mattress.

20 25 A further object of my invention is to provide a novel form of bed pan administration means, preferably associated with one of the parts of the bed, being clamped thereto by suitable clamps, said post having mounted thereon a combined slidable and rotary sleeve, which sleeve is equipped with a bed pan supporting arm, adapted to be raised and lowered with said sleeve, a suitable spring connecting said arm and sleeve 30 35 being used to hold said bed pan tightly in place when applied, said post being also provided with a loose collar capable of a rotary movement with said sleeve by means of a link and lever construction, whereby said 40 45 arm may be swung to one side when said pan is not in use, a suitable stop being provided on said post to prevent a sliding movement of said collar.

It is also within the province of my invention to provide my novel form of trap with a locking means and an actuating means for said locking means in the form of sets of toggles and levers whereby said locking means may be operated and the trap swung toward and away from the mattress with which it is associated.

The above and further objects of my invention as will hereinafter more fully appear, I attain with the apparatus constructed in accordance with the description in the

specification and illustrated in the drawings accompanying the same and forming my application.

Reference is had to the accompanying drawings, in which similar reference characters denote similar parts. In the drawings,

Fig. 1 is a fragmentary part side elevational and part sectional view of a bed showing my invention applied thereto, the dotted lines showing another position of the apparatus,

Fig. 2 is a fragmentary top plan view of the wire mattress equipped with my invention,

Fig. 3 is a top plan view, on a somewhat enlarged scale, of the trap and the framework of the wire mattress removed therefrom,

Fig. 4 is a side elevational view of the pad block adapted to be positioned on the trap,

Fig. 5 is a bottom plan view of Fig. 4,

Fig. 6 is a bottom plan view of the trap showing how the pad block may be secured thereto,

Fig. 7 is a front elevational view of the auxiliary post removed from the bed and showing the parts in elevated position,

Fig. 8 is a side elevational view of Fig. 7, looking from the right, but showing the parts in their lowermost position, and also the bed pan in dotted lines swung away from the patient,

Fig. 9 is an enlarged fragmentary part plan and part sectional detail view of the locking mechanism for the trap, and

Fig. 10 is a view similar to Fig. 7, but showing the parts in lowered position.

Describing my invention more in detail, the mattress pad 2 associated with the bed 4, which may be the usual hospital bed, has an opening 6, preferably in the shape of a truncated pyramid cut therefrom, as seen more particularly in Fig. 1, and, when the bed pan, hereinafter more particularly referred to, is not in use said opening is adapted to be closed by a complementary pad block 8, of the same configuration, so as to fit accurately in said opening, the top and bottom thereof being flush with the top and bottom of the mattress pad 2 so no objectionable protuberances will result. Said block pad 8 has a belt 10 equipped with suitable fasteners 12, which may be of the snap variety, stitched or otherwise associated with said pad block, so

80

100

105

110

that said pad block may be held in the mattress pad 2.

The bottom of the pad block 8 is also provided with tapes or strings 14, stitched or otherwise associated with said block, the ends of which are used to tie said block to the trap 16, presently to be more particularly referred to. Of course, any other means for detachably associating said pad block with the trap 16 may be substituted for that just described, and still remain within the province of my invention. It will be understood also that both sides of the pad block 8 are provided with a belt 10 and the fasteners 12.

15 The wire mattress 18 is cut away as more particularly shown in Fig. 2 to provide an opening in which is positioned a framework 20 of any desired shape, to which the wire springs 22 are secured, said frame work being 20 of metal, or any other suitable material, and to this frame work the trap 16 is hinged by the hinges 24, so that said trap may be swung away from the mattress in order that the bed pan 26 may be administered.

25 The trap 16 is made of a framework shaped to conform with the framework 20 of the mattress 18, and of a size to fit nicely therein (see Figs. 2 and 3), the wire cut away from the mattress being used as part of said trap, 30 it being of course understood that said trap may be otherwise constructed. As already explained, the pad block 8 is positioned on said trap, the tapes or strings 14, passing through slots 28 positioned in the framework 35 of said trap, said tapes being tied together as seen in Fig. 6.

The trap 16 is also provided with a locking means 30, shown more particularly in Fig. 9, for locking said trap in the framework 20 when the bed pan 26 is not in use. Means are also provided for not only operating said locking means, but also for swinging said trap out of the way when the bed pan is in use, said means being operable at a distance 45 from said trap, at any point desired.

As seen in Fig. 9, the frame work 20 is preferably made out of angle irons riveted or otherwise secured together, and the frame work of the trap 16 may be similarly constructed, angle irons 32, riveted to the frame work of said trap, being provided for supporting and guiding the locking elements 34, holes being provided in the angle irons 32 for this purpose. But two such locking devices are shown, but it will be clear that any preferred number may be employed.

The locking elements 34 are each provided with a flange 36, actuated by a spring 38, the angle iron 32 forming an abutment for 60 said spring, which spring constantly urges said locking element into the slots 40 and 42, as seen in Fig. 9, the outer end 44 of said elements being preferably curved to facilitate its passage through the slots 40 and 42, the 65 lower portion of said devices being flat and

this forms an effective lock for holding the trap 16 in closed position. Other locking means, however, may be employed instead of the structure just described.

The means for operating the locking means 30 preferably consists of a pair of toggles 46, pivoted to the framework of the trap, a link 48, each connected to one part of each toggle, and to the devices 34 being provided for operating said devices, the other ends of said toggles being connected together by an operating rod 50, connected to another toggle 52, pivoted to the operating lever 54, and adapted to be actuated by the link 56 and hand grip 58, associated with said lever, which rod 50 80 functions, when pulled by the toggle 52, through the link 56 and grip 58, simultaneously to cause the links 48 to withdraw the locking element 34 from the slots 40 and 42.

The lever 54 is secured to a rod 60, secured 85 in any desired manner to the hinged portion of the framework of the trap 16, a bearing 62 formed on the bed 4 being provided to support said rod and permit it to be turned therein so that said trap may be swung away from the opening in the wire mattress so that the bed pan may be administered, a pair of hooks or other devices 64 being provided to hold said lever in either position.

The bed pan administration means 95 comprises an auxiliary post 66, either solid or hollow, and preferably cylindrical, which post may be secured by suitable clamps 68 to one of the bed posts 70. See Fig. 1. This feature, however, is optional. On the auxiliary post 66 a sleeve 72 is mounted both for reciprocation or sliding movement and for rotary movement, a bent operating lever 74 being pivoted to said sleeve near its lower end. See Figs. 1, 7 and 8. The lever 74 is 105 provided with a pair of stops 76 to engage with a bar 78, pivoted to said lever and to a collar 80, also loosely mounted on the post 66, so as to prevent said lever from moving beyond a horizontal position when said lever 110 is moved to the right or left of said post.

The collar 80 is adapted to have a rotary movement, and may be rotated simultaneously with the sleeve 72, but said collar is not permitted a sliding movement, a stop 82, 115 preferably in the shape of a stationary collar secured to the post 66 preventing such movement. Any form of stop may be provided.

Hinged to the sleeve 72, and preferably at its lower position, is a bed pan supporting arm 84, which arm is equipped with a suitable support 86 of sufficient size to hold the pan 26, the character of said support being immaterial, and to prevent said arm from dropping, as well as to insure that said pan 125 will be closely applied to the bottom of the bed, a suitable spring 88 is provided, which spring is secured to the arm 84 and to the sleeve 72, as seen in Fig. 1.

In operation, when it is desired to admin-

ister the bed pan, the lever 54 is lifted from the forward hook 64 (Fig. 2) and the hand grip 58 pressed, which pressure pulls the link 56 downwardly, turning the toggle 52, which 5 pulls the rod 50, thus turning simultaneously the toggles 46, which in turn pull the links 48, depressing the springs 38, and releasing the locking elements 34, permitting the trap with its pad block 8 to drop, the fasteners 12 10 having been previously released. The lever 54 is now swung downwardly and then upwardly, positioning the same upon the rear hook 64, the trap with its pad having thus been swung close to the bottom of the wire 15 mattress, leaving an open space to the patient lying on the bed.

The arm 84, carrying the bed pan 26, is now swung from its dotted position shown in Figs. 1 and 8 so that said pan will be directly under the opening in the mattress. The lever 74 is then swung from its extreme left horizontal position to its extreme horizontal right position as seen in full lines in Figs. 1 and 7. This movement of said lever causes 25 the elevation of the sleeve 72, and the arm, to be lifted from the position shown in Figs. 1 and 7, bringing the pan 26 into close engagement with the hole in the mattress, the spring 38 securely holding said pan in such position.

30 After the pan has been used, the lever 74 is lifted to its extreme left position, thus lowering the sleeve 72, arm 84 and pan 26, after which the pan and arm may be swung to the dotted position shown in Fig. 1, the bar 35 78 permitting the collar 80 to rotate with the sleeve 72, the stops 76 in each case preventing the lever 74 from dropping too far. It will thus be seen that the amount of drop of the pan 26 is accurately limited.

30 To close the opening in the mattress the lever 54 is lifted from the rear hook 64 and swung downwardly, and then upwardly and positioned on the front hook 64, the hinged trap 16 being swung to to close the mattress, the locking devices being snapped into the slots 40 and 42, and the block pad 8 into the opening 6 of the pad 2, the fasteners 12 being snapped together.

45 While I have thus described my invention with great particularity, it will be clear that the same may be modified throughout a wide range. I accordingly do not propose to be limited to the exact details of construction shown and described, but reserve the right in practice to make any and all modifications thereof that fall within the scope of the appended claims.

I claim as my invention:

50 1. In a hospital bed, in combination, a wire mattress therefor, said mattress being provided with an opening, a trap door for opening and closing said opening, means associated with said door for operating the same, a pad for said mattress, said pad being provided with an opening in alignment with said

first opening, a pad block adapted optionally to be detachably positioned in said second opening or detachably secured to said trap door, fasteners on the sides of said block for detachably holding said block to said pad, 70 and means for detachably securing said block to said door.

2. In a hospital bed, bed pan administration means comprising an auxiliary post, a set of clamps for clamping said post to one of the posts of said bed, a swinging bed pan supporting arm, combined sliding and rotary means associated with said arm whereby said arm may be swung so that said pan will be placed in close proximity with the patient occupying said bed or away therefrom, and means for operating said combined sliding and rotary means.

3. A bed pan administration means for use in connection with hospital beds comprising 85 in combination a post adapted to be clamped to one of the posts of said bed, a sleeve adapted for sliding and rotary movement on said post, a collar adapted to be rotated on said post with said sleeve, means on said post for preventing a sliding movement of said collar, a bent lever pivoted to said sleeve, a link pivoted to said lever and said collar, and a bed pan supporting arm pivoted to said sleeve, 90 said lever functioning to raise or lower said sleeve so that said bed pan may be adjusted to the body of the patient occupying said bed, or said sleeve rotated so that said pan may be swung away from said patient.

4. In a device of the class described, a post 100 adapted to be rigidly secured to a support, a sleeve mounted on said post, a collar on said post, means connecting said collar and said sleeve whereby said sleeve and collar may be simultaneously rotated on said post and said sleeve raised or lowered on said post, a bed pan supporting arm pivoted to said sleeve, and a spring connecting said arm and said sleeve.

5. A bed pan administration means comprising a post adapted to be clamped to a bed, a sleeve adapted to be slid and rotated on said post, a lever pivoted to said sleeve, a collar loosely mounted on said post, a link connecting said lever and said collar whereby 110 said sleeve and said collar may be simultaneously rotated on said post, means on said post for preventing a sliding movement of said collar, a pair of stops on said lever for coacting with said link to prevent a further movement of said lever beyond a horizontal position when swung either to the right or left of said sleeve for raising or lowering the latter, and a bed pan carrying arm associated with said sleeve adapted to be raised 115 or lowered by said lever when the latter is swung to the right or left of said sleeve.

In testimony whereof I have signed my name to this specification.

CHRISTIAN H. HORST.
